UNITED STATES PATENT OFFICE.

ANDREW RAMSTAD, OF MERIDIAN, WISCONSIN.

GUIDE FOR FEEDERS FOR PLANING-MACHINES.

SPECIFICATION forming part of Letters Patent No. 364,542, dated June 7, 1887.

Application filed February 14, 1887. Serial No. 227,504. (No model.)

To all whom it may concern:

Be it known that I, ANDREW RAMSTAD, of Meridian, in the county of Dunn and State of Wisconsin, have invented certain new and useful Improvements in Guides for Feeders for Planing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a plan view of my improved guide for feeders for planing-machines. Fig. 2 is a side view of the same. Fig. 3 is a transverse sectional view taken on line $x-x$ of Fig. 1; and Fig. 4 is a vertical sectional view taken on line $Y-Y$ in Fig. 1, showing the mode of adjustment of the spring pressure-bar.

Like letters denote the same parts in all the figures.

My invention has relation to guides for feeders for planing-machines; and it consists in the improved construction and combination of parts of the same, as will be hereinafter more fully described and claimed.

In the accompanying drawings, the letter A denotes a frame constructed of any suitable material, having uprights B B at its forward end, provided, respectively, at their lower and upper portions with an aperture, C, and slot D, and having in their upper edges screw-threaded apertures E E. D' D' D' denote the curved cross-bars on the top of the frame, the two rear ones of which are provided with rectangular apertures F F. The axis of a feed-in roller, G, is journaled in the apertures C in the uprights, and one end is provided with a cog-wheel, H, having a fixed band-pulley, I, attached thereto. The slots in the upper ends of the uprights are adapted to receive journal-blocks J J, which receive the axis of a companion feed-in roller, K, which also is provided with a cog-wheel, L, upon one end, meshing with the lower cog-wheel, H. Placed above and below the journal-blocks are springs M M, which admit of the vertical play of the journal-blocks. Metallic plates N N are screwed to the upper ends of the uprights to prevent the journal-blocks from working out of the slots.

O indicates a guide-bar, secured to one side of the frame, and is preferably made of smooth steel; but any other suitable material may be used. P indicates a steel spring pressure-bar pivoted adjustably to the rear curved cross-bar, D', by means of a nutted bolt, Q, having a metallic plate, Q', secured rigidly thereto, and is adapted to be adjusted horizontally in the rectangular aperture F. A flat spring, R, is secured at one end to the plate Q' upon the rear cross-piece, while the opposite end having the slot R' is secured movably to the headed pin P' on the side of the spring pressure-bar P, so as to admit of a lateral movement of the said spring pressure-bar, which is provided at its free bifurcated end with a frictional roller, S.

T denotes a lever or handle, pivoted at its lower end to the bracket U in the rear end of the frame, having a connecting rod or pitman, V, secured with its rear end to the intermediate portion of the lever, and with its forward end to the cam W, pivoted adjustably by means of a nutted bolt, C', to the forward rectangular perforated cross-piece in the same manner as the spring pressure-bar, and is adapted to be adjusted in the same plane as the pressure-bar.

A plate, X, is secured to the bolt C' beneath the said cam, and has projecting upward therefrom a pin, Y, having a spring, B', secured thereto, the free end of which bears against the cam. A stud, A', projects upwardly from the rear portion of the plate and serves as a stop for the cam. The plates X and Q' are rigidly secured to their respective bolts, and are secured adjustably to the rear cross-pieces, D' D', by means of nuts X' and Q', clamping the said plates tightly against the said cross-pieces.

The operation of my invention is as follows: When it is desired to plane a board or plank, it is first placed upon the frame between the guide-bar and the spring pressure-bar with its end between the feed-in rollers G K. The lever is then pulled backward, and the cam is then forced back through the medium of the connecting-rod or pitman against the stud located on the plate which supports the said cam and bears against the intermediate face of the spring pressure-bar at right angles thereto, thus causing the said pressure-bar to curve slightly and force the friction-roller more firmly against the edge of the board or plank. While

the machine is in this position, the feed-rollers are made to rotate, thus feeding the plank or board straightly and firmly to the planing-machine. As soon as the plank or board passes the friction-roller in the end of the pressure-bar the strain upon the same is released and it suddenly springs to one side, and at the same instant the cam which has heretofore been at right angles to the spring pressure-bar is thrown suddenly forward by means of the spring B', and the spring R causes the said pressure-bar to be thrown slightly to the opposite side, as shown in dotted lines in Fig. 1, so as to enable another board or plank to be easily placed upon the frame between the fixed guide-bar and the said spring pressure-bar, when the operation as above described is performed.

It will be seen that by the use of the yielding spring pressure-bar boards or planks having no knotty edges can be fed through the rollers without binding, and when it is desired to feed boards or planks of a greater width to the planing-machine, the pressure-bar and the cam may be moved sidewise in the rectangular apertures 25 in the cross-bars and firmly held in place by means of the nutted bolts Q and C', but retain their relative positions to each other.

Having thus described my invention, I claim and desire to secure by Letters Patent of the

30 United States—

1. The combination, in a guide for feeders for planing-machines, of the fixed guide-bar, a pivoted yielding spring pressure-bar having a friction-roller at its free end, a cam adapted to bear with its free end against said spring pressure-bar, a lever, and a pitman connecting said

cam with said lever, substantially as shown and described.

2. The combination of the fixed guide-bar, the pivoted spring pressure-bar carrying a friction-roller at its free end, a cam adapted to bear against said spring pressure-bar and to be removed therefrom, and a lever connected with said cam and adapted to operate the same, substantially as and for the purpose shown and set forth.

3. The combination of the fixed guide-bar, a spring pressure-bar carrying a friction-roller at its free end, a spring connecting said pressure-bar with the frame of the machine, a spring-actuated cam adapted to lock the spring pressure-bar against the stuff to be fed through the machine, a lever, and a pitman connecting said cam with said lever, substantially as shown and described.

4. The combination of a frame having a fixed longitudinal guide-bar and longitudinally-slotted cross-bars, an adjustable spring pressure-bar having its bearing in one of the slotted cross-bars, and an adjustable spring-actuated cam adapted to be adjusted in unison with the spring pressure-bar and adapted to lock the friction-roller at the free end of said spring pressure-bar against the stuff to be fed through the machine, substantially as set forth.

In testimony that I claim the foregoing as my own I have hereunto affixed my signature in presence of two witnesses.

ANDREW RAMSTAD.
